UNITED STATES PATENT OFFICE.

WILLIAM G. COSTLEY, OF KENT, OHIO.

ADJUSTABLE DISPLAY-FRAME.

1,277,869.

Specification of Letters Patent. Patented Sept. 3, 1918.

Application filed August 6, 1917. Serial No. 184,737.

To all whom it may concern:

Be it known that I, WILLIAM G. COSTLEY, a citizen of the United States, residing in the city of Kent, in the county of Portage 5 and State of Ohio, have invented a certain new and useful Improvement in Adjustable Display-Frames, of which the following a full, clear, and exact description, reference being had to the accompanying 10 drawings.

The object of this invention is to provide a simple and inexpensive adjustable frame adapted to carry and display pictures or cards of various sizes. The frame is well 15 adapted for displaying posters, photographs, and notices relating to motion picture or theatrical productions. My display frame may conveniently be made of a suitable size for use in a theater lobby and carry one or 20 more large posters with various smaller photographs or cards at either side thereof. The frame may conveniently be made in an easel form and may be proportioned to take readily a number of existing standard sizes 25 of photographs on either side, and, in the intermediate portion, support larger pictures or posters of standard size.

In producing a frame to comply with the above requirements I have provided an intermediate portion having fixed vertical 30 edges and top and bottom, and laterally adjustable side portions which telescope with the intermediate portion. In the intermediate portion and the side portions I may provide one or more horizontal separators which 35 are adjustably positioned vertically. The separators on the side portions are telescoping to accommodate various widths of pictures. I provide also removable and 40 adjustable vertical separators which may be used between any of the horizontal separators. By this means I have produced a frame which is adaptable for displaying at one time photographs, posters, cards, notices, 45 etc., of a great variety of sizes and all arranged in appropriate relation. The frame is very neat in appearance, is easily adjusted and is very durable.

An embodiment of my frame adapted for 50 easel display in a theater lobby is illustrated in the drawings hereof and is hereinafter more fully explained. The essential characteristics of the invention, which are not limited to the particular form or proportions 55 shown, are summarized in the claims.

In the drawings, Figure 1 is a perspective

of the display frame carrying an illustrative arrangement of pictures; Fig. 2 is a perspective of the frame from the rear; Fig. 3 is a rear elevation of a portion of the frame adjacent to one edge; Fig. 4 is a vertical cross section, as indicated by the line 4-4 on Fig. 3; Fig. 5 is a horizontal cross section, as indicated by the line 5-5 on Fig. 3; Fig. 6 is a detail in rear elevation of one of the adjustable dividing members for the frame; Fig. 7 is an enlarged perspective of a portion of the frame adjacent to the outer edge looking from the front; Fig. 8 is a perspective of the end portion of one of the telescoping dividing members used in the intermediate portion of the frame.

Referring to Figs. 1, 2 and 3, A indicates what may be called the central panel of the frame, and B and C two side panels which 75 are formed to telescope laterally with the central panel. The central panel is formed with a suitable back plate D, permanent vertical side members E and E, a top G and a bottom H. Each of the side members is 80 formed with an outer vertical upright J, top and bottom members K and L which telescope into the central top G and bottom H respectively.

At the central panel between the vertical 85 edge members E are suitable horizontal separators M which may be located in any intermediate position desired. P indicates horizontal separators for the side panels B and C. These separators P are adjustable 90 to any position desired up and down and they telescope lengthwise of themselves. This enables the side panels to be shoved into the central panel or drawn out from it.

Referring now more particularly to the 95 means enabling the telescoping, it will be seen from Figs. 2, 3 and 4 that the top member G of the central panel is hollow, being made of a metal sheet bent to present a lower back portion 10 (secured to the back plate 100 D), a forwardly and downwardly inclined bottom portion 11, a flat front portion 12, a substantially horizontal top 13 and a back portion 14 which is spaced from the back portion 10 to leave a horizontal slot between 105 them. There is thus provided a flat open-ended slotted tube. The construction of the central bottom member H is the same except that the inclined portion faces upwardly and the horizontal edge 13 is at the 110 bottom.

The arms K and L of the side frame are

also flattened tubular members. Thus, as shown in Fig. 4, the arm K has a vertical portion 15, from the upper edge of which leads forwardly a downwardly inclined portion 16 and rising from the front edge of this a vertical portion 17. At the top of the portion 17 is a horizontal portion 18 and at the rear end of this a downward vertical portion 19, the lower end of which abuts 10 and may be secured to the junction of the parts 15 and 16. This arm is therefore a flattened tubular member with the flange 15 projecting from the inclined edge. The member L is similarly formed except that it 15 faces upwardly instead of downwardly.

The members K and L are of such size that they slide with reasonable snugness within the members G and H. This makes a comparatively stiff frame and at the same 20 time allows the lateral extension of the side panel. It also enables the members K and L to have substantially the appearance of continuations of the intermediate top and bottom members, as shown in Fig. 1.

25 To limit the extension of the side panels, I provide the slots referred to in the rear of the top and bottom members G and H and provide pins 20 on the members K and L occupying these slots and limiting the outward movement of the side panels.

It will be seen from the above described construction that the side panels may be collapsed until the inner edges thereof substantially abut the outer edges of the central 35 panel, or they may be drawn outwardly until the pins 20 abut the ends of the slots, as indicated at 21 in Fig. 3. The central panel has preferably a width about equal to twice that of the length of the arms K or 40 L so that the ends of such arms from the opposite side panels do not abut when the side panels are shoved in their innermost positions.

The telescoping horizontal separators P 45 which are adapted to be positioned in the side panels will now be described with particular reference to Figs. 2, 3, 5, 6 and 7. As shown in these figures, each of these separators P consists of two nesting trough-shaped members, that is to say, a front member having a flat portion 30, inwardly inclined top and bottom edges 31 and 32, and flanges 33 and 34 which extend vertically parallel with the front 30 from the rear 55 edges of the inclined portions 31 and 32. The other member 35 of this telescoping separator has a corresponding front portion 36, inclined top and bottom portions 37 and 38 and flanges 39 and 40. These two members 60 thus have a dove-tailed engagement with each other, allowing their telescoping while the two members act together as one stiff separating member whether collapsed or extended.

65 Secured to the rear face of the two mem-

bers 30 and 36 are a pair of upright strips 45 and 46. These strips may be readily soldered or otherwise secured to the flanges 33 and 34 in the case of the strip 45, and 39 and 40 in the case of the strip 46. Each of 70 the strips has secured to it rearwardly extending knobs 50 and 51. The shanks of these knobs are adapted to occupy vertical slots in the upright members E and J of the center and side panels. By this means the 75 ends of the telescoping separators are secured to the two uprights, but may shift up and down therein, while the telescoping of the separator on itself does not in the least interfere with the sliding of the side panel 80 in or out from the center panel.

The slots which the knobs 50 and 51 occupy are made in the forward wall of tubular members R carried at the outer edge of the rear of the central portion and tubular members 85 S carried at the inner edge of the rear of the side members J. These upright tubular guiding members R and S may be made and secured in place in any suitable manner. As shown, they are integral with the vertical 90 members E and J of the central and edge panels.

Referring more particularly to Fig. 5, it will be seen that the member E, forming the vertical edge of the central panel, and the 95 coöperating tubular guide R are both integral portions of the back plate D. Thus the back plate D is shown as bent rearwardly at 60 and then outwardly parallel with the main portion at 61, and then forwardly at 62, then inwardly at 63 parallel with the main portion D and overlapping the front thereof, and then outwardly at 64, then parallel with the main portion at 65 to provide the front of the upright edge member E and then from the inner edge of this member diagonally inwardly at 66 and then parallel with the front side of the back plate D at 67. This latter portion is a flange which may be secured directly to the back 100 plate. This construction provides the hollow upright frame bar E and the tubular guide R. The shanks of the knobs 51 occupy vertical slots 68 in the front face 63 of the tubular guide R.

The tubular guide S may, in a similar manner, be made an integral portion of the edge member J. As shown in Fig. 5 this integral structure is made of sheet metal bent as follows: A straight portion 70, then an inclined portion 71 from the forward edge of which leads the front part 72 to the member J, then a rearwardly extending portion 73, then a back portion 74 parallel with the portion 70, then a rearwardly extending portion 75; then a back portion 76, then a forwardly extending portion 77, then a front part 78 which alines the portion 70 and leaves a slot 79 between them. The overlapping parts 70 and 74 may conveniently be 110 120 125 130

soldered together. The construction provides a stiff tubular bar S having a vertical slot 79 which may be occupied by the shanks of the knobs 50.

- 5 It will be seen from the construction described that the two vertical tubular guides R and S may be integral portions of the corresponding upright members of the frame, and that these tubular bars provide vertical 10 slots which are occupied by the shanks of the knobs. The enlarged heads of these knobs within the tubular bars R and S hold the separator to the bars but enable it to be moved up and down thereof, as desired. 15 The slots in the bars R and S extend to the upper end thereof, enabling the knob shanks to be readily inserted.

Any suitable frictional means may be employed to hold the separators in whatever 20 vertical position they are given. We find it convenient for example, to secure leaf-springs 80 and 81 to the rear face of the flanges 39 and 34 of this telescoping separator. These leaf springs are adapted to 25 bear against the rear faces of the tubular bars R and S. When the separator is put in place from above, these leaf springs pass behind the bars R and S and bear against them with force to hold the separator in any 30 adjusted position.

It will be seen from the construction described that I may have as many of these separators P as desired in either side panel; that they may occupy any position up or 35 down as desired; that they do not interfere with the sliding of the side panel in or out, but follow it one way or the other. The inclined top and bottom of the separators, the inclined edges of the bars E and J and the 40 inclined edges of the top and bottom members K and L provide a set of rectangular spaces, each bounded by four overhanging edges. This enables any suitable card or picture to be put into such space and effectively held therein. The drawings, for 45 instance, show several cards or pictures T occupying these spaces.

The central panel has the flat back D and the overhanging vertical edges E and the 50 overhanging top and bottom G and H. This panel may therefore readily take one large poster sprung into place or otherwise secured with its edges behind the overhanging portions of the edge bars. However, it is 55 desirable frequently to provide several smaller posters or cards in this central space, as indicated by the cards U in Figs. 1 and 3. I provide for this by means of a separator M. These separators are preferably hollow 60 tubular metal members of the form shown in Figs. 3, 4 and 8. As there shown, each member M has an intermediate front portion 90 from the top and bottom edges of which extend inwardly inclined portions 91 65 and 92 from the rear edges of which extend

vertical flanges 93 and 94. Secured to the inner face of the intermediate portion 90 of these separators and projecting beyond the ends thereof are leaf-springs 95 which are preferably curved somewhat forwardly. 70 These separators are put in place first in a somewhat inclined position so that their overhanging springs may readily pass behind the members E, then they are turned up in a horizontal position and the springs 75 effectively hold them in place, providing as many panels as may be desired.

Should it be desired to divide any of the central spaces or side spaces vertically, this 80 can readily be done by members similar to the members M, but preferably shorter, which are suitably sprung into place between the adjacent separator members or between separator members and the top of the frame and the bottom of the frame as 85 the case may be. These vertical separators may thus be located at the central panel or in either of the side panels, as desired. I have indicated one of them in broken lines at Q in Fig. 3, which shows this vertical 90 separator in rear elevation between the two horizontal separators M. The vertical separator is put in place somewhat diagonal with its end springs underhanging the overhanging portions of the separators M and 95 then the vertical separator is trued up into position.

My adjustable frame may, if desired, hang on a wall, or it may stand on the floor as an easel, such being the frame shown in the 100 drawings. When it is desired to use it as an easel, the central panel preferably has two short legs V, while the lower ends of the vertical side members J are extended downwardly and provided with casters W. 105 This enables the side members to be readily slid in and out while the central portion remains stationary.

Any suitable means may be provided for supporting the back of the easel. Fig. 2 110 shows a tubular construction for this purpose made largely of gas piping and usual fittings as follows: 100, 101 and 102 indicate three gas pipes connected in an approximately U-shaped frame and hinged to the 115 upper portion of the back D by straps 103. 104 is a cross pipe from the legs 101 and 102, this cross pipe being swiveled in fittings 105 and 106 carried by the legs. Intermediately the bar 104 has a central fitting 108 through which slidably extends a brace 109 which is secured to a pipe 110 swiveled in elbows 111 and 112 secured to the back D. A suitable set-screw 115 carried by the fitting 108 clamps the brace 109 in any position 120 and thus holds the supporting member at the desired angle to the frame. The loosening of the set-screw allows the brace to slide through the fitting 108, thus enabling the legs to swing into parallelism with the 125 130

frame, the brace then depending substantially vertically through the fitting 108.

It will be seen from the above description that my frame may be comparatively 5 cheaply constructed and that it may be readily made of sheet metal bent by usual machinery into the form shown. If desired, some of the parts may be replaced by wood or other material, but I have found sheet 10 metal to operate very satisfactorily. I have found that by oxidizing the metal or covering it with an aluminum paint, the members which telescope into the others are not marred by contact with their fellows. 15 However, if desired, a sheet of fabric or other anti-friction material may be placed on the inner face of the larger member of the telescoping connection and thus 20 serve the member which draws out from undue rubbing.

Having thus described my invention what I claim is:

1. In an adjustable frame, the combination of an intermediate panel having two 25 upright edge members, a top member and a bottom member, and two side panels each provided with one edge member, a top member and a bottom member, the top and bottom members on the side panels being slidably 30 connected with the intermediate panel.

2. In an adjustable frame, the combination of a panel having an edge member, an adjustable panel having relatively fixed top, 35 bottom and outer edge members, said panel being slidably connected with the panel first mentioned, and a longitudinally extensible separator for the adjustable panel extending from the edge member first mentioned to the edge member of the adjustable panel.

40 3. In an adjustable frame, the combination of two picture carrying panels, means whereby one is adjustable laterally as a whole with reference to the other, and a longitudinally extensible separator carried 45 by the adjustable panel and dividing it into a plurality of picture carrying spaces.

4. In an adjustable display frame, the combination, with an intermediate panel, of two side panels telescoping into the intermediate panel, and telescoping separators 50 for the side panels.

5. In an adjustable display frame, the combination, with an intermediate panel, of two side panels adjustable bodily toward 55 and from the intermediate panel, and an adjustably positioned separator for the intermediate panel.

6. In an adjustable display frame, the combination, with an intermediate panel, of two side panels telescoping into the intermediate panel, telescoping separators for the side panels, and adjustably positioned separators for the intermediate panel.

7. The combination, with an intermediate panel, of side panels telescoping into the 65 intermediate panel, and transverse separators for the side panels telescoping on themselves, said separators being adjustably carried by the telescoping panels.

8. In a frame, the combination of a fixed 70 panel having hollow end members, adjustable panels on opposite sides thereof having end members sliding into the hollow fixed members, and movable separators for said panels.

75 9. In an adjustable frame, the combination of a central panel having supporting legs and side panels adjustable laterally with reference to the central panel and each provided with a supporting wheel.

80 10. The combination of a central panel having hollow top and bottom members, side panels having top and bottom members extending into the hollow top and bottom of the central member, legs supporting the central members and means supporting the side members, and telescoping horizontal separators for the side members.

85 11. The combination of a fixed panel having upright edge members and hollow top and bottom members, adjustable side panels having upright edge members and top and bottom members sliding into and out of the hollow members of the central panel, and telescoping separators carried between the 90 edge members of the central panel and the edge members of the side panels.

95 12. The combination of a panel having upright edge members and hollow top and bottom members, adjustable side panels having upright edge members and top and bottom members sliding into and out of the hollow members of the central panel, and telescoping separators carried between the 100 edge members of the central panel and the edge members of the side panels, said separators being adjustable bodily up and down and held in a given position by friction.

105 13. In a frame, the combination of an intermediate panel having edge members overhanging laterally in two directions and a pair of side panels adjustable in and out with reference to the intermediate panel, and having edge members overhanging on 110 their inner edges.

115 14. In a frame, the combination of an intermediate panel having vertical edge members overhanging laterally in two directions, side panels adjustable in and out with reference to the intermediate panel and having vertical edge members overhanging on their inner edges, and horizontal separators for the panels held by the overhang of the vertical edge members.

120 15. The combination of an intermediate panel having an upright edge member and

a hollow top and bottom, and a pair of side panels each having an upright edge member, top and bottom members for each side panel telescoping into top and bottom members of the panel first mentioned, said intermediate panel and edge panels each having a tubular vertical slotted bar adjacent to its edge, and telescoping separators for the side panel having means occupying the slots of

10 said bars.

16. In a display frame, the combination of a panel having a tubular bar with a slot in it, a side panel also having a tubular bar with a slot in it, a telescoping separator for 15 the side panel having means adapted to occupy said slots, and a leaf spring secured to the telescoping separator and adapted to bear against the rear face of one of the tubular bars.

20 17. The combination in a display frame of a panel having edge members which overhang, and a separator provided with projecting leaf springs at its ends which are adapted to engage behind the overhang of 25 the edge members.

18. In a display frame, the combination of a back for the frame, a tubular edge bar, and a tubular slotted guide all made of one integral piece of metal bent on itself, and a

separator having retaining means adapted 30 to occupy the slot.

19. In a frame, the combination of a back made of metal, and vertical edge bars formed by bending the metal on itself to make hollow tubular members in front of 35 the back, said tubular members overhanging toward each other, and an adjustably positioned separator having its ends held behind the overhang of the tubular members.

20. In an adjustable frame, the combination of an intermediate panel, side panels telescoping into the intermediate panel, and a support for the frame pivoted to the back of the intermediate panel, and means for holding said support at an angle to the 45 frame.

21. In a display frame, the combination of a central panel, side panels adapted to telescope therewith, a rear support for the central panel, the central panel being provided with supporting legs and each of the side panels having their outer edge members extended downwardly and provided with 50 wheels.

In testimony whereof I hereunto affix my 55 signature.

W. G. COSTLEY.
